UNITED STATES PATENT OFFICE.

PIOTR GIBA, OF CHICAGO, ILLINOIS.

PERMUTATION DOOR LOCK.

Application filed October 16, 1922. Serial No. 594,718.

To all whom it may concern:

Be it known that I, PIOTR GIBA, a citizen of Poland, residing at Chicago, in the county of Cook and State of Illinois, have invented 5 certain new and useful Improvements in Permutation Door Locks, of which the following is a specification.

This invention relates to locks, and more particularly to a keyless lock requiring that 10 the party desiring to open the lock, know the proper combination.

Another object of the invention is to provide a lock wherein the combination may be readily varied at the will of the user.

15 These objects are attained by the device herein described and shown in the accompanying drawings, in which:

Figure 1 is a fragmentary side view of a door showing an embodiment of the lock in 20 place therein.

Figure 2 is an edge view of Figure 1.

Figure 3 is a view similar to Figure 2, showing portions of the door broken away to illustrate the lock controlling discs.

25 Figure 4 is a longitudinal sectional view thru Fig. 1, showing the cover plate of the lock removed and portions of the locking discs broken away.

Figure 5 is a face view of one of the locking discs.

Figure 6 is a vertical sectional view taken on line 6—6 of Figure 5.

Figure 7 is a perspective view of the guide members of one of the locking discs.

35 Figure 8 is a perspective view of one of the locking discs, which co-operates with that shown in Figure 7.

Figure 9 is a transverse sectional view taken on line 9—9 of Figure 5.

40 In the drawings, the numeral 10 designates a door provided with an escutcheon plate 11 having formed therein a sight opening 12. The lock, designated generally by the numeral 13, is mortised into the door, as indicated by the dotted lines in Figure 1, also as illustrated in Figure 4, and contains the customary spring actuated latch 14, the movements of which are controlled by the spring 15 and the knob 16.

50 As illustrated in Figure 4, the body of the latch 14 is provided on opposite, longitudinal edges, with rack teeth in engagement with the pinion 17, through which the rectangular spindle of the knob 16 extends.

55 Mounted in parallel relation with the latch 14, is the locking bolt 18, provided on

its upper side with a plurality of rack teeth for engaging a pinion 19, mounted to rotate in the lock housing as shown.

This pinion 19 is provided with a central 60 rectangular opening for the reception of the lock bolt controlling knob 20, positioned on the exterior of the escutcheon plate as illustrated on Figures 1 and 2.

As shown in Figure 4, the bolt slides on 65 the guide 21, arranged within the lock casting, and is provided on its underside with a longitudinally extending rib 22, of lesser width than the thickness of the bolt. This rib is cut away at spaced intervals near its 70 rear end to provide a plurality of depending teeth 23, the purpose of which will be more fully described.

As shown in Figures 2, 3 and 5, the bolt 18 is substantially oblong in cross section and 75 is of a size to fit the openings 24 of the locking disc mountings.

Each locking disc is provided with an individual mounting, best illustrated in Figure 7, and comprises a disc 25 formed with 80 an opening 24 to receive the locking bolt 18. Extending from one face of each disc 25, is a cylindrical stud 26, provided with an opening in alignment with and in shape to conform with the opening 24. This stud forms 85 the bearing member of the locking disc, and as shown in Figure 7, the disc 25 is notched as at 27, to accommodate the rib 22 of the locking bolt.

Rotatably mounted on the bearing member 90 26, is a locking disc 28 provided with a notch 29, so that when the disc is in a certain position, the notch 29 aligns with the notch 27 and the bolt may be freely projected or withdrawn. Said disc 28 is provided with a central opening 30, to receive the stud 26, and extending radially from the disc 28 is a tooth 31 for a purpose to be described.

Rotatably mounted on the periphery of 100 the disc 25 is a ring 32 bearing the indicia 33, illustrated in Figures 1 and 4. A similar ring 34 surrounds the disc 28, and is provided on its inner face with a series of notches 35 for the reception of the tooth 31 105 of the disc 28.

It will thus be seen that as the ring 34 is rotated, the disc 28 will be moved correspondingly, but the ring 32 may be moved, without in any way affecting the locking 110 elements.

Due to the arrangement of the device on

the locking bolt, it will be obvious that the alternating rings will operate their respective locking discs, while the intermediate rings will rotate inoperatively on their respective mountings. As each ring is provided on its periphery with indicia 33, it will be obvious that the user must know which rings to move and also which numbers bring about the desired effect before 10 the bolt can be released.

Should an unauthorized person become acquainted with the combination, the user may, by disassembling the device, change the relative position of each ring 34, with its respective disc, by moving the position of the tooth 31 in the notches 35 and thereby re-arranging the combination without materially affecting the lock.

Although the foregoing is descriptive of 20 the preferred embodiment of the invention, it will be apparent that minor changes may be made in its construction, without the exercise of invention or conflicting with the scope of the claims hereto appended.

25 Having thus described by invention, what I claim as new and desire to secure by Letters Patent, is:—

1. A lock comprising a movable rectangular bolt, positive means for actuating said

bolt, a rib formed on one edge of said bolt, a plurality of bearing members mounted on the bolt, locking discs rotatably mounted on the bearing members, said locking discs being provided with notches, teeth on said rib arranged so that when the notches are 30 in alignment, the bolt will be free to move through the discs and their respective bearing members, and rings on the discs arranged to move the discs and rings on said bearing members.

2. A lock comprising a longitudinal movable rectangular bolt, positive means for projecting and withdrawing said bolt, a rib formed on one edge of said bolt, a plurality of bearing members slidably mounted on the bolt, locking discs rotatably mounted on the bearing members, said locking discs being provided with notches, teeth on said rib arranged so that when the notches of the discs are in alignment the bolt will be free to move through the discs and their respective bearing members, rings on the discs arranged to move the same, rings on the bearing members, and means adjustably connecting the discs with their respective rings 50 whereby the combination may be changed.

In witness whereof I affix my signature.
PIOTR GIBA.
